UNITED STATES PATENT OFFICE.

FREDERIC L. THOMPSON, OF NEW BEDFORD, MASSACHUSETTS, ASSIGNOR
TO THE PAIRPOINT MANUFACTURING COMPANY, OF SAME PLACE.

DESIGN FOR A SUPPORT FOR PITCHERS OR SIMILAR ARTICLES.

SPECIFICATION forming part of Design No. 23,681, dated October 9, 1894.

Application filed March 31, 1893. Serial No. 468,568. Term of patent 7 years.

To all whom it may concern:

Be it known that I, FREDERIC L. THOMPSON, a citizen of the United States, residing at New Bedford, in the county of Bristol and State of Massachusetts, have invented and produced a new and original Design for Support for Water-Pitchers and Similar Receptacles, of which the following is a specification, reference being had to the accompanying drawing, forming a part hereof and illustrating all the features of my new ornament or pattern.

The leading feature of my new design consists in the reversed, curved scrolls herein set forth.

15 A, A', A² and A³ are reversed scrolls which, being duplicated and connected on their opposed edges, form the base of one of the vertical sides of the support S. Scroll A is curved from 1 to 2; scroll A' from 3 to 4; scroll A² from 5 to 6; and scroll A³ from 7 to 8. The scrolls A, A', A² and A³ are best made in a single casting and may be used singly or be duplicated, as desired. Each casting which embraces the scrolls A, A', A² and A³, as shown, 25 has a side extension A⁴ and when the castings are duplicated, a space B is afforded between the inner edges of the combined scrolls; and the united projections A⁴ serve as a base for an ornamental figure D, if such is desired.

30 The compound scroll G, which forms half of that section of the support which is between the base portion (made up of the combined

cast scrolls above referred to) and the handle forming portion H, is composed of scrolls g, g', g² and g³. The compound scroll G is ordinarily a casting, and in the support shown, is duplicated, being united at its inner edges to a vertical bar g⁴. The compound scrolls G may of course be used singly, if desired, in various articles of manufacture, just as is the case with the cast scrolls embracing the portions A, A', A² and A³. From the duplicated, compound scrolls G rises a curved bar H, which, being duplicated, forms the handle of the support. This curved bar H is ornamented by the scrolls h, h', leaf h², the ornamented enlargement h³, leaf h⁴; and the bar terminates in the enlargement h⁵. This curved bar H is a casting, and when duplicated, the bars H are united at their ends h⁵, 50 and the other ends are joined to the desired article. It will be seen that the support, as a whole, is made up of the combined various scrolls already described, and two ornamental figures which occupy the clear space bounded by the inner edges of the duplicate scrolls A—A⁴ inclusive.

What I claim is—

The design for a pitcher or similar support herein shown and described.

FREDERIC L. THOMPSON.
